[57] CLAIM

The ornamental design for a bottle, as described and shown.

DESCRIPTION

FIG. 1 is an elevational view of a bottle embodying our new design, the opposite side being a mirror image thereof;

FIG. 2 is an elevational view looking from the left of FIG. 1;

FIG. 3 is a top plan view;

FIG. 4 is an elevational view looking from the right of FIG. 1; and

FIG. 5 is a bottom plan view.
